UNITED STATES PATENT OFFICE.

ALBERT J. BATES, OF JOLIET, ILLINOIS.

WIRE-BARBING MACHINE.

SPECIFICATION forming part of Letters Patent No. 357,653, dated February 15, 1887.

Application filed November 23, 1886. Serial No. 219,598. (No model.)

To all whom it may concern:

Be it known that I, ALBERT J. BATES, a citizen of the United States of America, residing at Joliet, in the county of Will and State 5 of Illinois, have invented certain new and useful Improvements in Wire-Barbing Machines, of which the following is a specification, reference being had therein to the accompanying drawings.

This invention relates to certain improvements in wire-barbing machines, the construction and operation of which are fully set forth and explained in the following specification and claims, reference being had to the accompanying drawings and the letters and figures of reference marked thereon, which form a part of this specification.

Referring to the drawings, Figure 1 is a perspective view, taken from one side of the machine, representing the machine as it appears when in operation. Fig. 2 is a top plan view of the machine. Fig. 3 is a detailed broken-away portion of the machine, looking at the corner thereof, as indicated by arrow 1 of Fig. 25. Fig. 4 is a similar view, looking at the corner of the machine, as indicated by arrow 2 of Fig. 2. Fig. 5 is a perspective view of the adjustable crank-disk of the machine for imparting motion to the barb-wire-feeding mechanism. Fig. 6 is a detailed broken-away portion of the machine, looking at the side thereof, as indicated by arrow 3 of Fig. 2, and representing a cross-section of the standard of the barb-wire-feeding mechanism, taken on 30 dotted line α of said figure. Fig. 7 is a vertical cross-section of the machine in front of the barb-coiling mechanism, taken on dotted line 4 of Fig. 2. Fig. 8 is a detailed view of one end of the sleeve of the barb-coiling mechanism of the machine, in which the center which guides the strand-wires is arranged, and of the barb-coiling pin, showing the manner of connecting said pin and sleeve. Fig. 9 is a rear plan view of the screw-cap and a cross-section 40 of the center and coiling-pin of the barb-coiling mechanism of the machine. Fig. 10 is a side view of the barb-coiling pin. Fig. 11 is a detailed view of a portion of the barb-coiling mechanism of the machine, showing a longitudinal section of the screw-cap, and also of a portion of both the sleeve and hub of the

coiling-pinion upon which the said screw-cap is fitted, also showing a side view of the barb-coiling pin and a portion of the center. Fig. 12 is a horizontal sectional view of the barb 55 coiling and cutting mechanism of the machine, taken on line 6 of Fig. 7, omitting the standard for supporting the stationary cutter; also showing a sectional part of the gear which imparts motion to the said coiling mechanism. 60 Fig. 13 is a perspective view of the center for guiding the strand-wires through the barb-coiling mechanism of the machine. Fig. 14 is an exterior view of the parts shown in section in Fig. 11; also showing the strand-wires 65 in position and the coiling-pin in the act of coiling a barb on the strand-wires, and also showing a portion of the stationary barb-cutter and one of the rotating barb-cutters. Fig. 15 is a face view of a disk having a face-stud, 70 upon which the gear supporting the rotating cutters of the machine is arranged, and through which the barb-coiling head is eccentrically arranged. Fig. 16 is a face view of the head which supports the barb-coiling mechanism 75 and the rotating barb-cutters of the machine. Fig. 17 is a central vertical longitudinal sectional view of the same. Fig. 18 is a detailed sectional view of the coiling-head of the machine. Fig. 19 is a face view of the same. 80 Fig. 20 is a detailed sectional view of a portion of the coiling-head mechanism of the machine; and Fig. 21 is a perspective view of a section of barbed wire, representing a product of the machine.

Referring to the drawings, B represents the bed of the machine, supported on suitable legs, M, which bed bears upon its upper surface the principal working parts of the machine.

R is the main drive-shaft, journaled in boxes 9c B' B'', and located at one side of the machine above the bed, as shown in Figs. 1 and 2. The end of said shaft next the twister T is provided with pinion G', which meshes with hollow pinion G of said twister, journaled in box T'. The opposite end of said shaft is provided with the pinions G² G⁴, which pinions drive the barbing parts of the machine. The extreme rear end of said shaft is provided with the crank-disk I, for driving the barb-wire feed. 95

H is a standard-box secured to the upper face of said bed, and is formed as shown in

Figs. 2, 12, 16, 17. This box contains the coiling-pinion G^3 , which meshes with pinion G^4 , which drives it. The chamber 2 of said box (shown in Figs. 12, 16, 17) forms a box for the rear part of the hub of said coiling-pinion, as shown in Fig. 12, and is long enough for containing a coil-spring, S^6 , to yieldingly press said coiling-pinion forward. A face-plate, h , secured to the face of said standard-box H by means of the bolts F , serves to secure said coiling-pinion therein, and forms a journal-bearing for the forward-extending part of the hub of said coiling-pinion, as shown in Fig. 12. The chamber 1 in said standard-box containing said coiling-pinion has sufficient depth to permit a reciprocating movement of said coiling-pinion therein. Said standard-box H is cut away at one side, as shown at I' , Figs. 16 and 17, so the coiling-pinion can mesh with pinion G^4 , as shown in Figs. 2 and 12 and in dotted lines in Fig. 7.

The plate h is provided on its outer face with an extending stud, h' , forming a spindle, upon which is placed the gear-wheel G^5 , which holds the rotating barb-cutters a and a' , and which meshes with pinion G^2 , and is held on said spindle or stud by means of the extending side flange, g , of said pinion G^2 , as shown in Figs. 2 and 7. Said stud has an aperture passing through it longitudinally, forming the journal for the forward end of the hub of the coiling-pinion, which aperture or journal is eccentric to the periphery of said stud, as shown in Fig. 15. The forward end of the hub of the coiling-pinion (shown at G^6) is reduced in size and screw-threaded, and C is a cap, of the same diameter, that screws on the screw-threaded outer end of said hub G^6 , as shown in Figs. 11, 12, 14. Said cap is reduced in diameter at its outer end, as shown in said figures, so it may not interfere with the stationary barb-cutter, as shown in Fig. 14, and is provided with a central longitudinal aperture for the reception of the outer end of the strand-wire guide C' , and a similar aperture at the side of said first-named aperture for the reception of the reciprocating coiling-pin b . When the cap C is thus screwed on the end of said hub, it becomes a part thereof, and the threads in it and on said hub are turned in the direction so that when said hub rotates it tightens said cap thereon and causes it to rotate therewith, and also carry the reciprocating coiling-pin b around the strand-wires. The cap C is made removable, so it can be replaced when worn without having to substitute an entire new coiling-pinion, and also for the purpose of rendering it easier to replace said coiling-pin by another when necessary. Figs. 7, 9, and 19 are face views of said cap, showing said apertures.

S is a reciprocating tube or sleeve arranged within the hub of said coiling-pinion, extending from the rear side of cap C through the rear part of standard-box H , as shown in Figs. 1, 2, and 12, and has secured on its rear end, by means of set-screw t' , the stud D , bearing a

friction-wheel, D' , for engaging with segment-cam D^2 on shaft R , by means of which cam said sleeve is reciprocated, as shown in Figs. 70 1, 2, and 12.

The coiling-pin b is located in a longitudinal aperture through cap C at one side from its center, and attaches to reciprocating sleeve S by means of the notch b' on its inner end, as shown in Figs. 11, 12, 18, and is reciprocated by means of said sleeve, which does not rotate. The cap C , containing said coiling-pin, having been screwed on the hub of coiling-pinion G^5 , as hereinbefore stated, really becomes a part thereof and rotates therewith, and necessarily rotates the coiling-pin b , both around said sleeve and the strand-wires passing through it, for the purpose of engaging the barb-prods to coil them around the strand-wires. 85

A removable strand-wire guide, C' , passes through said sleeve S , and is arranged therein so its forward end will be flush with the face of cap C , and its rear end extends a little beyond the end of said sleeve and is held secure therein by means of a set-screw, t . This strand-wire guide is provided with a pair of opposite channels, C' , extending from its rear end to near its forward end, where they connect with apertures extending through its forward end, as shown in Figs. 11, 12, and 13. These channels and apertures are for the reception of the strand-wires W and guide them through the coiling-pinion. 95

The pinion G^3 is provided with a pair of oppositely arranged adjustable rotating barb-cutters a and a' , held in their proper places by means of the set-screws n and n' , and are intended to shear with the stationary barb-cutter a' , seated in a channel in standard N , and held in place by cap-plate Q and proper cap-screws, as shown in Figs. 1 and 2; and immediately back of said cutter a' is secured a block, O' , which serves to properly guide the barb-prods past said standard N , and is adjusted by means of the set screw X . 100

N' is an extension of standard N , and arranged at a slight angle with bed B , as shown in Figs. 1 and 2, and is provided with a groove at one side for the reception of the reciprocating head J , having a spring gripping-dog, d , and a gripping-block, d' , for gripping and feeding forward intermittently the barbing-wire W^2 . (See Figs. 2 and 6.) A small guide or eyelet, d' , is attached to the extending part N' of standard N , as shown in Fig. 2, and is for the purpose of guiding the barbing-wire W^2 to the grip block d' . Said barb-feed is operated by means of crank-disk I through the medium of pitman P and lever L , as shown in Fig. 2. 115 120 125

At the time the barb-wire is first fed forward between the strand-wires the coiling-pin is withdrawn and the barb is fed forward to lie against the face of cap C . As soon as the feed is complete the coiling-pin emerges and, in its rotation with the coiling-pinion G^5 , catches the extending prod of the barb and coils it twice around the strand-wires, as shown in Figs. 14 and 21, the coil being made in the direction 130

toward the coiling-pinion, which is forced back by said coil as it is made. As soon as the coil is complete the cam D², through the medium of sleeve S, withdraws the coiling-pin within 5 the cap C, free from the barb, and at the same instant one of the rotating cutters of the wheel G³, in conjunction with stationary cutter A², severs the barb loose from the barb-wire W' in a diagonal manner, to form the opposite 10 prod of the barb, so that the barb will appear as shown in Fig. 21 when finished, and so that the next succeeding barb may be fed in across the face of the cap C, as stated. Said coiling-pinion is one-fourth the diameter of its drive-pinion G⁴, and consequently rotates four times the speed of said drive-pinion for the purpose of rotating the coiler twice each time it coils 15 on a barb. The wheel G³ rotates one-half way around while the coiling-pinion rotates four times—twice while coiling the barb and twice while withdrawn—and a barb is fed in and completed at each half-rotation of wheel G³, as it is provided with two oppositely arranged cutters, a a', each of which severs a barb loose when 20 they pass stationary cutter a².

The object of placing wheel G³ eccentrically with the coiling pinion, as stated, is to cause its cutters to pass near the strand-wires at the time the barb is severed loose and leave the 25 prod the proper length, and so the opposite cutter on said wheel will be such a distance from the coiling-pinion as not to be in the way of the barb-wire when it is first fed in and before it is coiled on the strand-wires.

30 In Figs. 18 and 20 a variation of the construction of the strand-wire guide C' is shown. In order to render it more easily made, the channels C⁴ may be continued through its whole length. Its forward end may be diminished in size a little way back for the reception 35 of the sleeve C⁸ on its diminished part, as shown in Fig. 20, the said channels being deep enough so the wires can pass in them through said sleeve C⁸, and the forward end, C', of said 40 sleeve can pass through to the front side of cap C, as shown in Fig. 19, and said sleeve can have formed on it the annular flange S' for holding in the coiling-pin, as in the other construction; but when the parts are all connected the device is mechanically the same in 45 both cases, the only advantage gained being that the guide can be made without having to bore the holes connecting with said channels.

In the construction of the barb-wire feed the 50 outer end of the pitman P is forked, as shown at P', Fig. 4, over a swivel-box, P², through which the end of lever L passes and slides, and the lower part of said box is provided with a slide which traverses in the guideway E, secured to the end of the machine-bed. Such construction prevents the outer end of the pitman from taking the curved motion of the lever L. The opposite end of said lever is provided with a guideway for the reception 55 of a swivel-slide, L', connected with the sliding head J. Such construction permits lever

L to reciprocate sliding head J in a straight line.

The disk I on the end of shaft R has pivotally secured to its face the plate I', by means of the screw V', at its lower side, and screw V, passing through slot V² in disk I. The wrist-pin U is secured to the face of said plate I'. By moving said plate I' from side to side at the top the wrist-pin may be placed and held at different distances from the center, and thus change the stroke of the feed. Figs. 2 and 5 show this construction. The butterfly-wheel Z² is journaled on the outer end of lever K, which is pivoted at its opposite end 75 on stud Y of standard A², and passes under cam E' on shaft R, as shown in Figs. 1 and 2. When cam E' rotates it will oscillate said lever and butterfly-wheel Z² between the stationary butterfly-wheels Z Z', for the purpose herein-after stated. 80

S³ is a coil spring connecting said lever K with the floor, for the purpose of preventing said lever and butterfly-wheel from rising too quickly when the cam E' rotates, and for 85 yielding holding said butterfly-wheel Z² on the strand-wires and preventing them from becoming slack.

Q is a loose pulley, and Q' is the drive-pulley, to which power is applied to drive the 90 machine.

In operation the strand-wires W W are threaded through the guide C' in its channels C⁴, and from thence over the two butterfly-wheels Z Z' and under oscillating butterfly-wheel Z² to the twister T. The barb-wire is intermittently fed in, by the barb-wire-feeding mechanism described, diagonally under the cutting-edge of the stationary cutter A², and so its fed-in point will pass between the two 100 strand-wires far enough so its end fed in will be long enough to be coiled around the strand-wires the required number of times and leave a prod of sufficient length uncoiled. The coiling-pin b then emerges, and in its rotation 105 around the strand-wires catches the barb-point fed in and coils it twice around the strand-wires in the direction toward the coiling-pinion, which is forced backward against the coil-spring S⁶ at its opposite end by the barb as 110 said coil is being made. At the instant the coil is finished the coiling-pin withdraws, and simultaneously one of the rotating barb-cutters, in conjunction with stationary cutter a², severs the barb in a diagonal manner loose 115 from the barb-wire. The oscillating butterfly-wheel then moves downward between the other two butterfly-wheels and draws the strand-wires along far enough for the next barb to be placed on in like manner. When a 120 barb is finished and moves on, the coiling-pinion is relieved from pressure of the barb and the spring behind it moves it forward and the coiling pin b reciprocates forward, by means of spring S⁴, and emerges from the coiling-pinion 125 after the next barb is fed in, and performs another like operation. 130

Having thus described my invention, what I claim as new, and desire to secure by Letters Patent, is as follows, to wit:

1. In a wire-barbing machine, in combination with a hollow wrapping-shaft having a barb-coiling pin and a stationary barb-cutter, rotating barb-cutters arranged eccentrically with said wrapping-shaft and said coiling-pin, substantially as and for the purpose set forth.
2. In the wire-barbing machine shown and described, the combination of the standard box H, having the plate h, provided with stud h', reciprocating coiling-pinion G⁵, reciprocating sleeve S, having the annular flange S', reciprocating coiling-pin b, having the notch b', wheel G³, having the barb-cutters a a' and arranged on said stud eccentrically with said coiling-pinion, stationary barb-cutter a², strand wire-guide C', having the channels C⁴, and the means, substantially as specified, for operating said parts and for feeding said strand and barb wires, as and for the purpose set forth.
3. In a wire-barbing machine, the combination of a continuously rotating and reciprocating coiling-pinion and coiling-pin, a stationary barb-cutter, and a pair of oppositely arranged rotating barb-cutters set to rotate eccentrically with said coiling-pinion and pin and to shear with said stationary cutter, substantially as and for the purpose set forth.
4. In the wire-barbing machine shown and described, and in combination with the reciprocating coiling-pinion G⁵ and the cap C thereof, the reciprocating sleeve S', and the coiling-pin b, having the notch b', for connecting said sleeve and pin, substantially as and for the purpose set forth.
5. In the wire-barbing machine shown and described, the combination of the coiling-pinion G⁵, having the cap C, sleeve S, coiling-pin b, strand-wire guide C', stud D, friction-roller D', cam D², and spring S', substantially as and for the purpose set forth.
6. In the wire-barbing machine shown and described, the combination of the sleeve S, having the annular flange S', and the coiling-pin b, having the notch b', for connecting said pin

and sleeve, so that said sleeve may reciprocate said pin, and said pin rotate around said sleeve, substantially as and for the purpose set forth.

7. In the wire-barbing machine shown and described, the combination of the gear-wheel G⁴, pinion G⁵, carrying coiling-pin b, gear-wheel G², and gear-wheel G³, having the barb-cutters a a' and stationary cutter a², as and for the purpose set forth.

8. In the wire-barbing machine shown and described, the combination of the sliding head J, provided with means for engaging the wire-guide N', lever L, and swiveled slide L', as and for the purpose set forth.

9. In the wire-barbing machine shown and described, and in combination with its barbing mechanism, the stationary butterfly-wheels Z and Z', and butterfly-wheel Z², arranged between said stationary butterfly-wheels and adapted to oscillate, substantially as and for the purpose set forth.

10. In the wire-barbing machine shown and described, and in combination with shaft R, having pinions G² G⁴, and cam D², the reciprocating coiling-pinion G⁵, wheel G³, having the barb-cutters a a', reciprocating sleeve S, having the coiling-pin b, strand-wire guide C', and stud D, provided with friction-wheel D', cap C, box H, plate h, and stationary barb-cutter a², substantially as and for the purpose set forth.

11. In the wire-barbing machine shown and described and in combination with the wire-barbing mechanism described, the barb-wire-feed mechanism consisting of the crank-disk I I', pitman P, having the swivel-box P', guide E, lever L, sliding head J, having the pivoted slide L', grip-dog d and grip-plate d², and guide N', all arranged to operate as and for the purpose set forth.

12. In the wire-barbing machine shown and described, the combination of arm K, cam E', spring S³, and butterfly-wheels Z, Z', and Z², as and for the purpose set forth.

ALBERT J. BATES.
